UNITED STATES PATENT OFFICE

JAMES J. TINKER, OF SAN DIEGO, CALIFORNIA

AMALGAMATOR

Application filed January 19, 1926, Serial No. 82,195. Renewed January 15, 1930.

My invention is an amalgamator for use in the separation of fine gold from auriferous material when such material is in a very fine state such as the product from quartz, stamp mills or black sand, the soil from placer mines or any pulverized ores or gangues from which gold has been originally obtained. My amalgamator in some cases can rework sufficiently the tailings from prior operations.

An object of my invention is to produce an amalgamator in which the consumption of mercury is considerably reduced compared with the amount of amalgam products and in which the amount of mercury carried off by the tailings is also reduced.

A further feature of my invention is to expose the material being treated to the action of mercury so that in practice substantially all particles of gold in the material being treated is subjected to the action of the mercury to thereby form an amalgam.

Some of the specific features of my invention are the mounting of the plates for carrying the material under treatment so that these may be accurately adjusted to any suitable angle; also providing mercury troughs that may be accurately adjusted in relation to the plates, and splash plates which may also be adjusted properly in relation to the troughs and to the plates.

A further feature of my invention is to provide for a mercury overflow leading from one end of the amalgamator so that this overflow may be readily collected from each of the troughs, and also to provide a simple arrangement for conducting a solution such as sodium or alkali solution to the troughs.

In constructing my amalgamator I utilize a simple wood framing having posts at the end. These posts have attached thereto a bracket for supporting the plates, these latter being carried by a frame. Arcuate guide brackets are attached to the posts to accurately adjust and clamp the plates at the proper inclination. The troughs are carried by pivoted arms mounted on the plate brackets so that the troughs may be elevated and adjusted towards and from the plates. Splash plates are also carried by studs ex-

tending outwardly from the posts and may be adjusted vertically or horizontally.

I prefer to conduct the overflow mercury from the troughs by rubber hose leading to overflow pipes and to feed the sodium solution to the troughs by means of a rubber hose connection from a suitable tank.

My invention will be more readily understood from the following description and drawings, in which:

Fig. 1 is a rear elevation of Fig. 2, taken in the direction of the arrow 1 of Fig. 2, showing certain details in section.

Fig. 2 is a vertical transverse section of Fig. 1, on the line 2—2, in the direction of the arrows.

Fig. 3 is a plan view of Figs. 1 or 2, in the direction of the arrows 3.

Fig. 4 is a detail perspective view of the plate supporting brackets and the trough supporting arms.

Fig. 5 is a perspective detail of the attachment of the troughs to the arms, as if viewed in the direction of the arrow 5 of Fig. 4.

Fig. 6 is a perspective detail of one of the guide brackets for adjusting the inclination of the plates.

Fig. 7 is a perspective detail of the adjustable mounting for the splash plates.

Fig. 8 is a diagrammatic view showing the manner of conducting the alkali solution to the troughs.

Fig. 9 is a diagrammatic longitudinal section of the trough, showing the feeding arrangement for the alkali solution.

The framing of my amalgamator is constructed substantially as follows, having reference particularly to Figs. 1, 2 and 3:

A base 1 is formed of cross timbers 2 and longitudinal timbers 3 and supports at each end a pair of posts 4. These posts have a capping piece 5, which may also be braced to a structure having a chute for feeding the material to be treated. The various elements of the frame are securely bolted or otherwise secured together and form a simple structure for mounting the various features of my amalgamator.

The plates are mounted substantially as follows:

The plates are designated by the numeral 6 and are preferably copper plates silver plated having an upturned side rim 7 and an upturned end rim 8, leaving the lower end 9 free to allow the run off of the material under treatment. A plate bracket 10 is bolted to the posts, this bracket being shown particularly in Figs. 1, 2 and 4. The bracket consists substantially of a channel in which the web 11 is secured to the posts, the lower flange 12 is formed with a semi-circular bearing 13 formed by a depression. A lug 14 extends upwardly from the upper flange 15. These plate brackets are secured on the inside of the posts at opposite ends of the machine. The plates are suitably supported on a frame 16 having a longitudinal bar 17 at the center, this bar being supported at each end in the bearings 13. Side angle bars 18 and 19 support 20 the plate near the longitudinal edges and a rod 20 having rivets 21 at each end is secured to the side angles 18 and 19.

Guide brackets 22, shown particularly in Figs. 1, 2, and 6 are secured to the side edges 25 of the posts. These brackets have flattened ends 23 and 24 for the insertion of screws and have an arcuate surface 25 conforming to the curve drawn on the radius from the bearings 13 so that the angle 19 extended will ride on this surface. A slot 26 is formed in the face 25 and a cross slot 27 in the curved portion 28 of the guide bracket. This allows the insertion of a clamping nut 29 with the head through the cross slot 27, thereby clamping 35 the side angle 19 to the guide bracket.

Therefore it will be seen that the adjustment of the plate to secure the proper inclination may be readily accomplished by loosening the nut 29 at the end posts and adjusting 40 the plates until the proper flow of material desired is obtained. In the construction shown I utilize five plates discharging the material being treated alternately on opposite sides of the amalgamator, however as shown, 45 the front and the back of the machine will be unencumbered so that the operator readily has access to either side for adjusting the plates or the other parts of the mechanism to be hereunder described.

50 The construction and mounting of the mercury troughs is substantially as follows, having reference particularly to Figs. 1, 2 and 3: The troughs 30 are in the form of channels having a web 31 with side flanges 32 and preferably have a slight downward extension 33 to the flanges. The troughs have closure plate 34 at each end. Straps 35 are bolted to the closure plates, thus forming a suspension 55 for the troughs, this being illustrated in detail in Figs. 4 and 5. Trough adjusting arms 36 are pivotally mounted on the lug 14 and have a handle 37 to form a ready adjustment, this handle being split and having a longitudinal slot 38 to engage the stud 39 on the straps 35. A thumb nut 40 is utilized to clamp

the studs and hence the straps 35 and troughs at the proper horizontal distance from the edge of the troughs by sliding the stud in and out in the slot 38. The vertical adjustment of the troughs is through the medium of a slot 41 through which passes a bolt 42 having a thumb nut 43, the bolt being secured to one of the posts whereby when the arm is elevated to the proper position, the thumb nut may be clamped, thereby supporting the troughs in 75 the proper relative position to the discharge edge of the plates.

The splash plates are constructed and mounted substantially as follows, having reference particularly to Figs. 1, 2 and 7:

The splash plate 44 is located running longitudinally above the troughs and spaced slightly from the discharge end of the plates to guide the material running off the plate into the troughs. The plate has a block 45 secured to each end through which extends a right angled arm 46, a thumb screw 47 clamping the block to the arm to secure vertical adjustment of the splash plate. The horizontal adjustment of the splash plate is by 80 means of the stud 48 having a bolt end 49 rigidly bolted to one of the posts and having a head 50 through which the arm 46 may slide, a set screw 51 being utilized to clamp the arm in any desired horizontal position. 85

It will thus be seen by the construction so far described that all the plates may be adjusted at suitable inclinations; that each of the troughs may be adjusted vertically and horizontally into the proper relation to the edge of the plates and that the splash plates adjacent the discharge edge of each plate may be adjusted vertically and horizontally into proper relation, both to the plates and to the troughs.

The material undergoing treatment in the form of a slime flows down the chute 52 into the screen trough 53. This trough has the usual perforations distributed along its length to properly slide the slime and pass it to the uppermost plate. This trough is adjustable by having straps 54 extending upwardly and by means of slots 55 and thumb screws 56, the troughs may be adjusted to the relative elevation above the uppermost plate. 105

The mercury overflow is handled in the following manner, as illustrated particularly in Figs. 1, 2 and 3.

A stand pipe 57 extends vertically upwardly at one end of the amalgamator and has a series of branch pipes 58 with cups 59 at the top of the branch pipes. A rubber hose 60 is connected to one end of each trough as indicated by the numeral 61 and discharges into these cups. Eyes 62, having stems 63 are secured in blocks 64 on the end posts and are adjusted to different elevations by the thumb screws 65. The adjustment to control the overflow of mercury is by raising and lowering the eyes and thereby changing the ele- 130

vation of the discharge end of the rubber overflow hose in relation to the troughs. Each overflow hose may thus be accurately adjusted to the proper elevation.

5 The arrangement for flowing the alkali solution preferably a sodium solution, is indicated in Figs. 8 and 9. A tank 66 is suitably mounted on one of the end frames or on the end posts and is shown as having five discharge tubes 67 with valves 68 therein. 10 Rubber tubes 69 extend from these discharge tubes to a T 70 having a spray pipe 71 attached thereto, this spray pipe being positioned above the troughs and adjusted in proper relation by being secured to the splash plates in any suitable manner.

It will thus be seen that by the control valve 68, the amount of solution passing to each trough may be accurately gauged and controlled and that the amount of solution flowing into each trough may be controlled independently of that flowing into other troughs.

25 The general operation of my amalgamator is substantially as follows:

It will be understood that the plates, the troughs and the splash plates require to be accurately adjusted to obtain the proper flow of the slimes over the plates and into the mercury troughs and that for certain ores the travel must be much slower than for others and also that it must differ sometimes in different portions of the machine by having a different inclination of the plates. The zigzag arrangement of flowing the slimes downwardly brings the particles of gold in contact with the amalgamating surfaces and as these materials overflow the troughs the flow is changed in direction, therefore the tendency is that any particles which may pass an upper surface without being subject to the amalgam will contact with a lower surface.

45 It will be understood that the heavy material accumulating in the troughs will be cleaned out periodically by scrapers or the like and that the mercury is kept in a pure condition by a proper adjustment of the flow of the compositions used for purifying the mercury such as sodium as above described.

Although my amalgamator is of comparatively simple structure so far as the individual elements composing it are concerned, nevertheless these may be considerably changed in general structure and in detail as well as the general design of the amalgamator may be changed to suit particular circumstances or conditions of operation. Such changes in the general features or specific details will be within the scope of my invention as set forth in the description, drawings and claims.

Having described my invention, what I claim is:

65 1. In an amalgamator, end posts forming

a supporting structure, a pair of plate brackets each substantially channel shaped and having a depression in the lower flange forming a bearing, a plate supported in a frame, said frame having a central longitudinal bar pivotally mounted in the said bearings, the said frame having side angle bars with connecting rods between the side bars and the central bar, one of the side bars being extended beyond the plate over the outside of one of the posts, and means on the post to engage the extension of the side bar and adjust the inclination of the plate. 70

2. In an amalgamator as claimed in claim 1, in which the means mounted on the post comprises a guide bracket having an arcuate surface, a slot in said bracket and a clamping bolt to clamp the extension of the side bar to the said guide bracket. 80

3. In an amalgamator a pair of end post constructions, a plate bracket secured to each of the posts, each of said brackets having a semi-circular bearing, a frame having a longitudinal bar in the center, said bar being pivotally mounted in the said bearings, a plate supported on the said frame, a guide bracket secured to one of the posts, and means interconnecting the guide bracket and the frame to adjust the inclination of the plate. 90

4. In an amalgamator, as claimed in claim 3, a lug extending upwardly from one of the brackets, a trough adjusting arm pivotally mounted on the lug, said arm having a longitudinal slot and a vertical slot, means extending through the vertical slot connected to one of the posts to clamp the arm in various positions in regard to the post, and a trough suspended from the arm, having means engaging in the longitudinal slot. 100

In testimony whereof I have signed my name to this specification.

JAMES J. TINKER.
